CLAIM

The ornamental design for a post cap, as shown and described.

DESCRIPTION

FIG. 1 is an isometric view of a post cap showing my new design.

FIG. 2 is a side elevational view thereof, which is the same for each side of the post cap.

FIG. 3 is a top plan view thereof.

FIG. 4 is a bottom plan view thereof; and,

FIG. 5 is a bottom perspective view thereof.

Stippling and contour lines shown in the drawings are intended to represent the approximate three-dimensional contours of the design, and are not intended to indicate surface decoration. The broken lines in the figures are for illustrative purposes only and form no part of the claimed design.
